UNITED STATES PATENT OFFICE.

WILLIAM H. HOLMES, OF COLUMBUS, OHIO.

BED-SPRING-DIVIDING MEMBER.

1,230,406.

Specification of Letters Patent. Patented June 19, 1917.

Application filed June 13, 1916. Serial No. 103,392.

To all whom it may concern:

Be it known that I, WILLIAM H. HOLMES, a citizen of the United States, residing at Columbus, in the county of Franklin and State of Ohio, have invented a certain new and useful Improvement in Bed-Spring-Dividing Members, of which the following is a specification.

With the common form of woven wire bed spring as now in general use the fabric necessarily sags; and when two occupy the bed there is a tendency to crowd uncomfortably together. Permanent means have been proposed for stiffening the fabric longitudinally along the middle of the fabric so that each side can sag independently of the other and thus form a ridge that will prevent the sleepers from rolling together, but such means are not suitable when one person only is to occupy the bed and it is agreeable not to be confined to one side thereof. The object of my invention, therefore, is to provide a dividing member of simple and economical form that can with equal facility be manipulated to place it either into position to form such a dividing ridge or relaxed to avoid its formation.

The invention is embodied in the construction herein shown and described and then finally claimed.

In the accompanying drawing forming part hereof,

Figure 1 is a top plan view of the bed spring showing my invention applied thereto, portions only of the fabric being shown.

Fig. 2 is a longitudinally sectional view on the line II—II Fig. 1.

Fig. 3 is a detail view on a larger scale showing the means for stretching and relaxing the dividing member.

Fig. 4 is a perspective view of one of the hooks employed in the construction.

In the views 5 designates the ordinary metallic bed spring frame, and 6 an ordinary woven wire spring fabric attached to the head and foot rails of the frame by coil springs 7. The frame members or rails are commonly formed of angle bars.

I provide hook members 8 and 9 to embrace the head and foot rails respectively, said hook members having their shanks each provided with several pairs of holes as seen at 10. The dividing member consists mainly of a stiff wire 11 having at one end a coil spring 12 and at the other end a link 13. The end of the dividing

member having the coil spring 12 is connected with the hook 8 by means of another hook 14 of stiff wire, such as shown in Fig. 4, which is engaged with the hook 8 by passing the free ends thereof up through the spring fabric and a pair of the holes 10 as illustrated in Fig. 2. At the other end of the dividing member is a hook member 15 similar to that marked 14 to similarly engage the hook 9 except that the hook member 15 is bent in its shank to form an additional hook portion 15^a which when in operative position inclines toward the adjacent rail. Said hook portion is to be engaged by the hook 13 when the dividing member 11 is brought up into working position as hereinafter described. Pivottally attached to the hook portion 15^a is a lever 16 having its upper or shorter arm terminating in a nose 16^a and on its longer arm a hook 16^b about midway of its length.

In Figs. 2 and 3 the dividing member and the operating parts are indicated by full lines as in the position when the member is taut, and in broken lines as in the relaxed position. To bring the dividing member into taut position the lever is simply pulled up to full line position and when so pulled up the link 13 engages the hook portion 15^a. To relax the dividing member the longer arm of the lever is depressed and when this is done the nose 16^a engages the link 13 and draws it out of engagement with the hook portion 15^a after which the dividing member falls leaving the link engaged with the hook 16^b.

The dividing member can be made more or less taut as desired by shifting the hooks 8 and 9 or either of them to another pair of the holes 10.

The ridge is, of course, formed when the fabric is depressed at each side of the dividing member by the weight of the persons occupying the bed.

The details are susceptible of modification without departing from the gist of the invention as claimed.

What I claim is,

1. Means for dividing a bed spring longitudinally substantially as described consisting of a detachable strand applied beneath the mattress and adapted to have supporting contact therewith, means for attaching one end of said strand to one end of the spring frame and means for attaching the other end of the strand to the opposite end

of said frame including a hook and a coöperating lever for engaging the strand with said hook and disengaging the strand therefrom.

5 2. Means for dividing a bed spring longitudinally substantially as described consisting of a detachable strand applied beneath the mattress and adapted to have supporting contact therewith, means for attaching 10 one end of said strand to one end of the spring frame and means for attaching the other end of the strand to the opposite end of said frame including a hook and a lever fulcrumed in said hook for engaging the 15 strand with said hook and disengaging the strand therefrom.

3. Means for dividing a bed spring longitudinally substantially as described consisting of a detachable strand applied beneath the mattress and adapted to have supporting 20 contact therewith, means for attaching one end of said strand to one end of the spring frame and means for attaching the other end of the strand to the opposite end of said frame including a hook and a coöperating lever for engaging the strand with said hook and disengaging the strand therefrom and means on said lever for retaining the strand engaged with the lever when disengaged 25 from the hook.

WILLIAM H. HOLMES
